His Attorney.

UNITED STATES PATENT OFFICE

2,418,470

LATCHING MECHANISM FOR ELECTRIC SWITCHES

Winton G. Harlow, Upper Darby, Pa., assignor to
General Electric Company, a corporation of New
York

Application July 27, 1945, Serial No. 607,371

9 Claims. (Cl. 200—169)

1

My invention relates to improvements in latching mechanisms for electric switches and more particularly switches which are used to isolate or disconnect electric apparatus from the source of power. Such switches are known to the art as disconnecting switches, knife switches and the like.

Such switches often have to conduct large currents especially when overloads or faults occur on the circuit with which the switches are associated. The high magnetic stresses consequent upon the loop expansion effect tend to open the switches. Also, when such switches are used on warcraft and the like, shocks due to explosions, gunfire, etc. tend to open the switches. Inasmuch as such switches are not intended to interrupt the circuit during overload or fault conditions, it is necessary to prevent their opening under the action of both magnetic stresses and shocks and particularly so on warcraft since both are likely to occur simultaneously. Moreover, the interruption of a circuit by a switch under such conditions, even if the switch were not seriously damaged or destroyed, might well prove disastrous during battle conditions. Also, switches in the open circuit position may be undesirably closed in consequence of shocks, force of gravity, etc. In order to prevent such undesirable opening and closing of these switches, many latching mechanisms for holding the switch conducting members in the closed or open circuit position have been devised. Some of these have been unsatisfactory, others are limited in their application, and still others would not hold the switch conducting members in the open or closed circuit positions under shocks.

An object of my invention is to provide for isolating switches an improved latching mechanism which will positively hold the movable conducting members of the switch in one or more desired circuit controlling positions against the effects of shocks, gravity and magnetic stresses. Another object of my invention is to provide a latching mechanism which is equally applicable to single or double throw switches without change in the switch structure itself. A further object of my invention is to provide a latching mechanism which is relatively simple and easy to operate and economical to manufacture. These and other objects of my invention will appear in more detail hereinafter.

In accordance with my invention, I provide for an isolating switch a dynamically balanced latching member which is biased to latching engagement with an opening in the handle mounted

2

on the free ends of the movable switch conducting members. Also in accordance with my invention, I provide an element movably positioned in the opening in the switch handle for releasing the latching member under pressure of the operator's fingers on a release bar slidably mounted in a recess in the switch handle. Further in accordance with my invention, I provide a latching mechanism which is readily applicable without change in switch structure to either a single or a double throw switch or to a single throw switch which is to be held in both the circuit open and circuit closed positions.

My invention will be better understood from the following description when considered in connection with the accompanying drawing, and its scope will be pointed out in the appended claims.

In the accompanying drawing, Fig. 1 illustrates a vertical front elevation of a double pole, single throw switch provided with a latching mechanism embodying my invention; Fig. 2 is a side elevation of the switch shown in Fig. 1; Fig. 3 is a sectional elevation on the line 3—3 of Fig. 1 to an enlarged scale showing the latching mechanism in the latched position; and Fig. 4 is a sectional elevation similar to Fig. 3 showing the latching mechanism in the released position.

In Figs. 1 and 2, I have shown, for the purpose of illustrating my invention, an isolating switch of the disconnecting or knife blade type comprising at least two spaced conducting elements 1 pivotally mounted on a base 2 of insulating material as at 3 and 4 on suitable hinge studs 5 for movement about a common axis. As shown, each conducting element comprises two parallel blade members 6, which in the closed circuit position embrace contact studs 7. In order to insure firm contact between the blades 6 and the stud 7 especially under shock conditions, the blades are resiliently interconnected adjacent the stud by suitable means such as a bolt 6' passing through spring washers 7' in engagement with the blades. For manually actuating the blades 1 to and from the circuit closed position, their free ends are suitably secured to a handle 8 provided with a longitudinal finger channel 9 and thumb channels 10. For better gripping, these channels may be ribbed, as shown.

For holding the blades 1 in one or more predetermined circuit controlling positions, I provide a latching mechanism which, as shown, comprises a bushing 11 mounted in the handle 8 transversely thereof and provided with a longitudinal opening 12. The bushing 11 may be screwed into the handle 8, as shown. Cooperat-

ing with the bushing 11 is a latching member 13 which is adapted for latching engagement in the opening 12 in the bushing. Thus, for example, the latching member 13 is provided with a projection such as a cylindrical boss 14 which fits into the opening 12, as shown in Fig. 3.

Further in accordance with my invention, I provide means adapted to be mounted on the switch base 2 for pivotally supporting the latching member 13 in a position to cause latching engagement of the boss 14 and the bushing 11 when the blades are moved to a predetermined position. As shown, this means comprises a U-shaped member 15, the base of which is welded or otherwise suitably secured to a threaded post 16. The sides 17 of the member 15 may be provided with lugs 18 which project into suitable openings 19 in the base to prevent turning, and a nut 20 and suitable washers 21, one of which is a lock washer, serve to maintain the latch supporting means in position. Between the sides of the U-shaped member 15 there is mounted a pivot 22 for the latching member 13 and around this pivot there is mounted suitable biasing means such as a looped torsion spring 23 which biases the latching member 13 to the latching position shown in Fig. 3. For shock-proof purposes, the latching member 13 is pivotally supported at its center of gravity whereby to obtain dynamical balance about its pivotal axis 22. For this purpose, the lower end of the latching member 13 is extended and provided with counterweighting portions 24.

For limiting the rotation of the latching member in the latch engaging direction, counter-clockwise as viewed in Figs. 3 and 4, the pivot 22 may be positioned as shown so that the extension of the latching member bears against the supporting post 16 as shown in Fig. 3. Further in order to stop the blades 1 in a predetermined position such as to secure the desired latching engagement, I mount between the sides 17 of the U-shaped member 15 a stop 25 against which the handle 8 comes to rest in the closed position of the switch as shown in Fig. 3. In the illustrated embodiment of my invention, the stop 25 also serves as an abutment for the looped end of the spring 23. If it is desired to latch the switch blades 1 in both the open and closed positions, then two latching members 13 and the supports therefor are mounted on the base, one on each side of the pivotal axis of the blades as shown in Figs. 1 and 2. Similarly, for a double throw switch, one latching member 13 and its support are provided for each throw of the switch.

For releasing the latching member 13 from latching engagement with the bushing 11 in the normal process of gripping the handle 8 to open the switch, this handle is provided with a longitudinal recess 26 for the reception of a latch releasing bar 27. This bar is rigidly secured to a plunger 28 which is movably mounted in the path of movement of the latching projection 14 in a portion of reduced diameter of the longitudinal opening 12 in the bushing 11. The releasing bar 27 is preferably long enough so as to be engageable by more than one finger in order that the operator can readily release the latching member 13 without hunting for the end of the plunger 28 to press down with the right finger. Also in order to prevent escape of the releasing bar and turning thereof, it is of a similar configuration as the recess 26 in the handle and the plunger 28 is provided with an enlarged head 29 which fits the latch receiving portion of the bush-

ing opening 12. The releasing bar 27 is suitably secured to the plunger 28 at the other end at such a distance from the plunger head 29 that the bar 27 cannot escape from its recess and yet is still convenient for finger pressure to release the latching member. For easy engagement of the projection 14 in the opening 12 in the bushing 11, the outer surface 30 of that portion of the bushing which is engaged by the projection 14 near the end of the blade movement is preferably beveled as shown whereby to move the latching member 13 clockwise, as viewed in Figs. 3 and 4, against the bias thereon.

Assuming now that the switch is closed as shown in Figs. 1 and 2, then upon placing the fingers in the finger channel 9 of the handle 8 and pressing inwardly on the release bar 27, it will be apparent that the plunger 28 is moved from the left to right, as viewed in Fig. 3, to move the latch engaging member 13 from the latching position shown in Fig. 3 to the released position shown in Fig. 4. When the latch engaging member 13 is in the released position, a pull on the handle 8 opens the switch. The switch may be then swung around into its other position, the lower position as shown in Figs. 1 and 2, whereupon the latch engaging member in the lower position will enter the opening 12 in the bushing 11 to latch the switch in such other position.

While I have shown and described my invention in considerable detail, I do not desire to be limited to the exact arrangement shown, but seek to cover in the appended claims all those modifications that fall within the true spirit and scope of my invention.

What I claim as new and desire to secure by Letters Patent of the United States is:

1. In a latching mechanism for a switch having at least two spaced conducting elements pivotally mounted on a base, a handle secured to the free ends of said conducting elements, a bushing mounted in the handle transversely thereof and provided with a longitudinal opening, a latching member adapted for latching engagement in the opening in said bushing, means adapted to be mounted on the switch base for pivotally supporting said latching member in a position to cause latching engagement of the member and said bushing when said elements are moved to a predetermined position, and means adapted to be operated to disengage said member from latching engagement with said bushing comprising a plunger movably mounted in the opening in the bushing and engageable with the latching member for release thereof upon movement of the plunger in one direction.

2. In a latching mechanism for a switch having at least two spaced conducting elements pivotally mounted on a base, a handle secured to the free ends of said conductor elements, a bushing mounted in the handle transversely thereof and provided with a longitudinal opening, a latching member adapted for latching engagement in the opening in said bushing, means adapted to be mounted on the switch base for pivotally supporting said latching member in a position to cause latching engagement of the member and said bushing when said elements are moved to a predetermined position including means for stopping the elements in said position, and means adapted to be operated to disengage said member from latching engagement with said bushing comprising a plunger movably mounted in the opening in the bushing and engageable

with the latching member for release thereof upon movement of the plunger in one direction.

3. In a latching mechanism for a switch having at least two spaced conducting elements pivotally mounted on a base, a handle secured to the free ends of said conductor elements, a bushing mounted in the handle transversely thereof and provided with a longitudinal opening, a latching member provided with a projection for latching engagement in the opening in said bushing, means adapted to be mounted on the switch base for pivotally supporting said latching member in a position to cause latching engagement of said projection and said bushing when said elements are moved to a predetermined position, and means adapted to be operated to move said projection out of the opening in said bushing comprising a plunger movably mounted in the opening in the bushing and having one end engageable with the projection on the latching member for release thereof upon movement of the plunger in one direction.

4. In a latching mechanism for a switch having at least two spaced blades pivotally supported on a base for movement about a common axis, a handle secured to the free ends of the blades, a bushing mounted in said handle transversely thereof intermediate said blades and provided with a longitudinal opening, a latching member provided with a projection for latching engagement in the opening in said bushing, means adapted to be mounted on the switch base for pivotally supporting said latching member in a position to cause latching engagement of said projection and said bushing when the blades are moved to a predetermined position including means for stopping the blades in said position and means for biasing the latching member into latching engagement with the bushing, and means adapted to be operated to move said projection out of the opening in said bushing comprising a plunger movably mounted in the opening in the bushing and having one end engageable with the projection on said latching member for release thereof upon movement of the plunger in one direction.

5. In a latching mechanism for a switch having at least two spaced conducting elements pivotally mounted on a base, a handle secured to the free ends of said conductor elements and having a longitudinal finger channel provided with a longitudinal recess, a bushing extending transversely into the handle substantially midway of the recess therein and provided with a longitudinal opening, a latching member provided with a projection for latching engagement in the opening in said bushing, means adapted to be mounted on the switch base for pivotally supporting said latching member in a position to cause latching engagement of said projection and said bushing when the blades are moved to a predetermined position, means adapted to be operated to move said projection out of the opening in said bushing comprising a plunger movably mounted in the opening in the bushing and having one end provided with a releasing bar shaped to fit the recess in said handle and positioned in such recess for a limited movement substantially only transversely of the handle, the other end of said plunger being engageable with the projection on the latching member for release thereof upon movement of the releasing bar toward the bottom of the recess in the handle.

6. In a latching mechanism for a switch having at least two spaced conducting elements piv-

totally mounted on a base, a handle secured to the free ends of said conductor elements, a bushing mounted in the handle transversely thereof and provided with a longitudinal opening, a latching member adapted for latching engagement in the opening in said bushing, means adapted to be mounted on the switch base for pivotally supporting said latching member in a position to cause latching engagement of the member and said bushing when the blades are moved to a predetermined position including means for stopping the blades in said position, an inclined surface on said bushing engageable with said latching member to move the latching member against the bias thereon as the blades are moved to said predetermined position, and means adapted to be operated to disengage said member from latching engagement with said bushing comprising a plunger movably mounted in the opening in the bushing and engageable with the latching member for release thereof upon movement of the plunger in one direction.

7. In a latching mechanism for a switch having at least two spaced blades pivotally supported on a base for movement about a common axis, a handle secured to the free ends of the blades, a bushing mounted in said handle transversely thereof intermediate said blades and provided with a longitudinal opening, a latching member provided with a projection for latching engagement in the opening in said bushing, means adapted to be mounted on the switch base for pivotally supporting said latching member in a position to cause latching engagement of said projection and said bushing when the blades are moved to a predetermined position including means for stopping the blades in said position and means for biasing the latching member into latching engagement with the bushing, an inclined face on said bushing engageable with said projection for moving said latching member against the bias thereon as the blades are moved to said predetermined position, and means adapted to be operated to move said projection out of the opening in said bushing comprising a plunger movably mounted in the opening in the bushing and having one end engageable with the projection on said latching member for release thereof upon movement of the plunger in one direction.

8. In a latching mechanism for a switch having conducting elements pivotally mounted on a base, a handle secured to the free ends of said elements and provided with a transverse opening, a latching member adapted for latching engagement in the opening in said handle, means adapted to be mounted on the switch base for pivotally supporting said latching member in a position to cause latching engagement of the member and said handle when said elements are moved to a predetermined position, and means adapted to be operated to disengage said member from latching engagement with said handle comprising a plunger slidably positioned in the opening in said handle and engageable with the latching member for release thereof upon movement of the plunger in one direction.

9. In a latching mechanism for a switch having conducting elements pivotally mounted on a base, a handle secured to the free ends of said elements, said handle having a longitudinal finger channel provided with a longitudinal recess and a transverse opening connecting with said recess, a latching member adapted for latching engagement in the opening in said handle, means adapted to be mounted on the switch base for

pivottally supporting said latching member in a position to cause latching engagement of the member and said handle when said elements are moved to a predetermined position, means adapted to be operated to disengage said member from latching engagement with said handle comprising a plunger slidably positioned in the transverse

opening in the bushing and having one end engageable with the latching member and the other end provided with a releasing bar shaped to fit the recess in said handle and positioned in such recess for limited movement substantially only transversely of the handle.

WINTON G. HARLOW.
